UNITED STATES PATENT OFFICE.

MARTIN SZINAK, OF CINCINNATI, OHIO.

FOLDING BED.

1,157,453.

Specification of Letters Patent. Patented Oct. 19, 1915.

Application filed April 26, 1915. Serial No. 23,884.

To all whom it may concern:

Be it known that I, MARTIN SZINAK, subject of the King of Hungary, residing at Cincinnati, in the county of Hamilton and State of Ohio, have invented certain new and useful Improvements in Folding Beds, of which the following is a specification.

This invention relates to certain new and useful improvements in folding beds.

The primary object of this invention is to provide a foldable bed structure in which the complete mechanism is housed in an upright arrangement adapted for fitting against the wall of a room where the structure may be readily unfolded in its bed formation.

A still further object is to provide a folding bed which is incapable of collapsing or falling over when in its open operative position, thus obviating any possible injury to the sleeping occupant of the bed.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like-designating characters refer to corresponding parts throughout the several views: Figure 1 is a perspective view of the bedstead in its open operative position. Fig. 2 is a side elevation of the device closed shown partially in vertical section and parts being broken away. Fig. 3 is an enlarged side view of the strut engagement. Fig. 4 is a perspective view of the engaging end of the strut. Fig. 5 is an enlarged detail view of a side portion of the central hinge portion, and Fig. 6 is a perspective view of the strut connections and their swinging attachment to the central hinge bar.

Referring more in detail to the drawings, it is designed to arrange the head member 10 of the bed in the form of a box shaped casing, and the foot member 11 in the form of a closure lid for the same, and the bed frame structure is adapted for being inclosed within the head casing.

A head frame 12 is hinged as at 13 within the casing 10, while a similar frame 14 is hinged as at 15 to the foot 11. Hinged plates 16 are carried by the adjacent rails 17 of the two frames 12 and 14 and are connected by a

hinged bar 18, and in which manner the frames are hinged together. Metal legs 19 for the bed are arranged swingingly mounted upon the opposite ends of the said bar 18 and in this manner the frames 12 and 14 will be horizontally positioned in bedstead formation supported by the central legs 19 and the legs 20 of the head casing 10, and the legs 21 of the foot board 11.

Depending brackets 22 are centrally carried by both the head and foot members and are U-shaped in cross-section having inclined slots 23 in their opposite sides adapted for the sliding reception of rods 24 at the outer free ends of strut bars 25 and 26 arranged at opposite ends of the bed. The strut 25 being positioned beneath the foot frame 14, its free end 27 is journaled centrally upon the hinged bar 18, while the other strut 26 which engages the bracket of the head casing has a hinged connection 28 with the strut 25 adjacent its upper end and upon the lower face thereof.

The slots 23 of the brackets 22 have inwardly extending notches or recesses 29 at their lower ends in which notches, cross rods 24 of the struts are adapted to engage when the bed is in its open position, thus preventing the same from accidentally collapsing or falling over.

When it is desired to close the bed, the struts 25 and 26 have the rods 24 thereof disengaged from the slot notches 29 and seated upon the shoulders 30 at the inner sides of the slots 23 and whereupon the casing 10 being held stationary as against the side wall of the room, the foot board 11 may be moved toward the same, thus folding the mechanism within the casing 10 as best illustrated in Fig. 2 and allowing the hasps 30 carried by the casing to be engaged with the hook 32, of the foot board 11. It will thus be seen that the bed frame structure may be readily closed and unfolded whenever desired and a serviceable and foldable piece of furniture is thereby provided.

While the form of the invention herein shown and described is what is believed to be the preferred embodiment thereof, it is nevertheless to be understood that minor changes may be made without departing from the spirit and scope of the invention as claimed.

What I claim as new is:

1. A foldable bed comprising an open sided head casing, a centrally depending

- bracket carried thereby having opposite inclined slots, a foot board arranged opposite the open side of the said casing and being of substantially the same dimensions as the 5 said opening, a depending bracket upon the said board provided with inwardly inclined opposite slots, similar bottom frames hinged adjacent the lower inner sides of the said casing and board, a transversely-arranged hinge bar between the said frames, central legs swingingly mounted upon the opposite ends of the said hinged bar, struts hingedly connected together and one of the same being pivoted to the said hinge bar, and rods 10 upon the outer free ends of the said struts slidably mounted within the said bracket slots.
2. A device of the class described, comprising a head casing being open at the 15 lower front sides thereof, head legs for the bed mounted upon the said casing, a depending bracket U-shaped in cross section centrally depending from the said casing and having inwardly inclined opposite slots 20 therein terminating at their lower ends in inwardly extending notches, a foot board

adapted for reception within the open inner side of the said casing, and oppositely arranged with respect thereto, legs for the said bed upon the said foot board, a bracket centrally depending from the said foot board and having inwardly inclined slots provided 30 with notches at their lower ends, similar rectangular bed bottom frames hingedly connected adjacent the lower inner sides of the 35 said casing and board, a central transversely arranged hinged bar between the said frames, central legs for the bed swingingly mounted upon the opposite ends of the said bar, a strut having one end journaled to the said 40 hinged bar, and extending adjacent the said foot board bracket, a relatively longer strut hingedly connected to the first-named strut adjacent its upper end and having its free 45 end extending adjacent the said casing bracket, transverse end rods upon the said struts in sliding engagement within the said bracket slots and seated within the said slot notches when the bed is in its operative 50 unfolded position.

In testimony whereof I affix my signature.
MARTIN SZINAK.
